US0D1046762S

(12) **United States Design Patent** (10) Patent No.: **US D1,046,762 S**
(45) Date of Patent: ** Oct. 15, 2024

(54) **SOLAR POWERED ELECTRONIC DISPLAY ASSEMBLY WITH POLE MOUNT**

(56)

CLAIM

The ornamental design for a solar powered electronic display assembly with pole mount, as shown and described.

DESCRIPTION

FIG. 1 is a front perspective view of a solar powered electronic display assembly with pole mount;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a perspective environmental view thereof.

The broken lines shown represent environmental subject matter and form no part of the claimed design. The dot-dashed broken line(s) define the bounds of the claimed design and form no part thereof.
